UNITED STATES PATENT OFFICE

WILLIAM L. SMITH, JR., AND ROBERT H. LAWSON, OF PAWTUCKET, RHODE ISLAND;
SAID SMITH ASSIGNOR TO MAY HOISERY MILLS, OF NASHVILLE, TENNESSEE, A
CORPORATION OF TENNESSEE

DIAL AND CYLINDER CONNECTION FOR KNITTING MACHINES

Original application filed February 21, 1930, Serial No. 430,436. Divided and this application filed
March 10, 1931. Serial No. 521,578.

This invention relates to dial and cylinder connections in knitting machines and particularly to the means of mounting and driving the dial cams in the machine.

5 An object of the invention is to provide a driving connection in which the dial assemblage as a whole may be easily lifted out of its operative position in the cylinder for purposes of inspection and repair and a further 10 object is to provide a driving connection in which the dial needles will always be driven in perfect synchronism with the cylinder needles.

This application is a division of our co- 15 pending application Serial No. 430,436, filed February 21, 1930, for knitting machines.

Referring to the accompanying drawings which are made a part hereof and on which similar reference characters indicate similar 20 parts,

Figure 1 is a view partly in section of the dial and cylinder and cams for controlling the dial needles,

Figure 2, a plan view of Figure 1,

25 Figure 3, a fragmentary sectional view of the needle dial,

Figure 4, a view partly in section of the driving connection between the needles, cylinder and the dial,

30 Figure 5, a plan view of the devices shown in Figure 3, and

Figure 6, a section on line 6—6 of Figure 4 showing means for circumferential adjustment of the dial driving shaft.

35 As shown in Figure 1 a dial 10 is secured upon a dial post 11. A dial cam 12 is carried on the lower end of a shaft 13 which shaft is vertically slidable in a bracket 14 which is attached to and forms part of a dial cap 15.

40 Surrounding the shaft 13 at its upper end is a coil spring 16 seated in a socket in the upper end of the bracket 14. The lower end of the spring engages a shoulder in the socket and the upper end engages an arm 17 fastened to the upper end of the shaft 13. The free end of the arm 17 carries a pin 18. The spring 16 tends normally to maintain the cam 12 in engagement with the lower face of the dial cap 15 and when in this position the cam

45 may engage the longer butts on dial needles

as more fully explained in the parent application. The pin 18 projects through one arm of a lever 19. The lever is pivoted upon a sleeve surrounding the shaft 11 which supports the dial. The lever is operated by suitable mechanism such as that in the application referred to for operating cam 12.

55 The driving connections between the needle and dial whereby the dial is driven in a fixed circumferential relation with the cylinder will now be described. A ring gear 20 is seated and supported by the circular base 21 which base is stationary and provides a bearing support for the ring gear. Fastened to and forming a part of the ring gear 20 is a spur gear 22. A circular plate 23 is connected to the base 21 and overhangs the spur gear 22 serving to hold it and the ring gear 20 in place, the spur gear 22 meshes with an intermediate gear or pinion 24 which

pinion is journaled in the base 21. The gear 24 in turn meshes with a second spur gear 25. The intermediate gear 24 is removably connected to the circular base 21 by a bracket 26 secured at its ends by screws 27 and 28, 60 the latter of which passes through a slot 29 formed in one end of the bracket. The bracket 26 has a sleeve or bearing 30 which carries a stub shaft 31 formed as an extension of the gear 21 and attached to the upper end of the shaft 31 is a head pin 32 provided with a reduced shank portion 33.

65 Semi-circular plates 34 are fastened to the sleeve 30 by screws 35 and engage under the head of the pin 32 so that upon removal of the screws 27, 28 the entire bracket and spur gear may be raised bodily from the ring gear and removed from the machine. As previously stated intermediate gear 24 meshes with a spur gear 25. The gear 25 is made 70 integral with or connected to a sleeve 36, the sleeve 36 surrounding a sleeve 37. The sleeve 36 is secured to the sleeve 37 by means of set screws 38 which engage two arms 39 on the sleeve 37. The arms are formed by cutting away or removing portions of the sleeve at opposite sides. The set screws 38 are secured in place by locking screws 40. The sleeve 37 is splined to a shaft 41 by a key 75

42 which seats in a keyway 43 cut in the 80

shaft 41. The sleeve 36 is secured to the dial 10 by a set screw 44 which passes through the dial 10 and sleeve 36 and engages a shoulder in the sleeve 36.

85 The dial 10 is secured to the dial post 11 by a set screw 45 which passes through the dial 10 and dial post 11 and engages a shoulder in the dial post 11.

90 The dial 10 is secured to the dial post 11 by a set screw 46 which passes through the dial 10 and dial post 11 and engages a shoulder in the dial post 11.

95 The dial 10 is secured to the dial post 11 by a set screw 47 which passes through the dial 10 and dial post 11 and engages a shoulder in the dial post 11.

100 The dial 10 is secured to the dial post 11 by a set screw 48 which passes through the dial 10 and dial post 11 and engages a shoulder in the dial post 11.

shaft 41. The shaft 41 extends upwardly and is provided adjacent its upper end with threads 44 to which is secured a collar 45 by means of screws 46. The collar rests 5 against a thrust bearing 47 seated in the upper end of the dial supporting post 48.

At the upper end of the shaft 41 is fixed a spiral gear 48 which meshes with a second spiral gear 49 carried by one end of a shaft 10 50, journaled in bearings 51. At its other end the shaft 50 has a spiral gear 52 meshing with a spiral gear 53 on the upper end of the shaft 11. Casings or guards 54 and 55 cover the several gears 48, 49, 52 and 53 15 as well as the connecting shaft 50. Fixed to the shaft 11 immediately beneath the gear 53 is a collar 56 having a flange 57 and immediately beneath the flange is a thrust bearing 58 to take care of the downward thrust due 20 to the rotation of the dial. A bifurcated plate 59 seats upon the upper surface of the flange 57. Two arms of the plate partly encircle the collar 56 and act to take the upward thrust of the shaft 11. The plate 59 is rigidly attached to a collar 60 which collar forms the outer end of a bracket arm 61 which is connected to the dial supporting post 47. The collar 60 is fastened to a sleeve 62 which forms a part of the bracket 14 to 25 which latter bracket is rigidly connected dial cap 15. The bracket 14 also serves to provide bearings for shafts 13 and 63. The bracket 14 provides in conjunction with the sleeve 62 a bearing for the dial supporting 30 shaft 11. The dial 10 is supported upon the lower end of the shaft 11 to rotate therewith by means of a hub or sleeve 64, which hub is made integral with the dial and depends therefrom. The hub is fastened to the shaft 40 11 by means of set screws 65. Surrounding the hub 64 is sleeve 66 which is recessed and made fast to the hub 64 by means of a screw 67. The sleeve 66 is recessed at 68 to permit ready connection and disconnection of 45 the dial 10 from the shaft 11 and the recess also provides an indication for properly aligning the dial and cylinder so that the long, medium and short ended dial needles may be positioned in the right track grooves 50 in the needle dial as more fully described in the application of which this is a division. A recess 69 provides means whereby auxiliary take-up hooks not shown may engage the fabric during knitting of heel and toe 55 pockets and maintain a tension upon the stitches so that the dial needles when introduced will cast off their made stitches. This feature, however, forms no part of the present invention, but is referred to to give a more 60 complete understanding of the structure shown.

It will be obvious to those skilled in the art, that various changes may be made in our device without departing from the spirit of 65 the invention and therefore we do not limit

ourselves to what is shown in the drawings and described in the specification, but only as indicated by the appended claims.

Having thus fully described our said invention, what we claim as new and desire to secure by Letters Patent, is:

1. In a knitting machine of the character described, including a needle dial and a needle cylinder, means for rotating the dial in time with the said cylinder including a train of gears comprising a ring gear attached to for driving the said cylinder, a gear secured to the said ring gear, a shaft operably connected to the dial, a gear on said shaft, an intermediate gear between said last-named gear and the gear on the ring gear, all of said last-named gears lying in a single plane, substantially as set forth.

2. In a knitting machine of the character described, including a needle dial and a needle cylinder, means for rotating the dial in time with the cylinder including a train of gears consisting of a driven gear, an intermediate gear and a sleeve provided with gear teeth, the intermediate gear in mesh with the gear first mentioned and with the teeth upon the sleeve, a vertically disposed shaft within the sleeve and driven thereby, a gear carried by the shaft at the upper end thereof, a second and horizontally disposed shaft, a gear thereon, a gear adjacent the other end of the horizontally disposed shaft, a third shaft vertically disposed, a gear adjacent the upper end thereof in mesh with the gear last mentioned, the dial fast to the shaft third mentioned at the lower end thereof substantially as set forth.

In witness whereof, we have hereunto set our hands and seals at Pawtucket, Rhode Island this 5th day of March, A. D. nineteen hundred and thirty-one.

WILLIAM L. SMITH, JR.
ROBERT H. LAWSON.
